UNITED STATES PATENT OFFICE.

REUBEN R. ERICH, OF SAN JOSE, CALIFORNIA.

CANNING-MACHINE.

1,391,307.

Specification of Letters Patent. Patented Sept. 20, 1921.

Application filed February 1, 1921. Serial No. 441,648.

To all whom it may concern:

Be it known that I, REUBEN R. ERICH, a citizen of the United States, and resident of San Jose, in the county of Santa Clara and State of California, have invented certain new and useful Improvements in Canning-Machines, of which the following is a specification.

My invention relates primarily to a machine for use in canning soft pulpy material in large tins.

In the fruit canning industry a somewhat large proportion of the fruit such as apricots, peaches, etc., is reduced to a pulpy mass not suitable for canning in small tins for sale through the usual channels. The material in this form is commonly known as "pie" and is put up in large containers, usually gallon tin cans. In canning "pie" in accordance with present practice it is fed into a hopper from a cooker and then the individual cans are filled from the hopper by means of an ordinary sliding gate. This method is not only unsanitary and wasteful but in a very large percentage of cases the material is deposited in the can in such a manner as to trap a large quantity of steam therein. The result of this procedure is that when the can is capped and allowed to cool the consequent reduction of the steam to water so far reduces the internal pressure of the can that it collapses and must be discarded and some or all of its contents lost. This loss of cans through collapsing is especially large in the branch of the canning industry referred to because gallon cans are used almost to the entire exclusion of other sizes, and since these cans are made of the same weight of tin as the smaller cans their increased size renders them proportionately less able to resist an excess of pressure on either side.

It is the object of my invention to provide a machine for canning material of the character indicated which will be sanitary, positive in action, simple in construction and operation, which will eliminate waste of material during canning thereof, and which will reduce the loss of cans through trapping of excess steam therein to a minimum.

In the drawings:

Figure 1 is a side elevation of my improved canning machine, partly in section.

Fig. 2 is a view on line 2-2 of Fig. 1, part broken away.

Referring more particularly to the draw-

ing, I show at 1 a hopper supported in any suitable manner not shown over a table 2 and having a cylindrical chamber 3 arranged therein. Chamber 3 is closed at the top, has a diameter of substantially the same size as the cans to be filled, and is open at the bottom as indicated at 4. Chamber 3 also has a plurality of openings as 5 formed in its side walls and at its lower end and communicating with the hopper 1.

At 6 is shown a plunger operating in chamber 3 and arranged to move through the distance 7 closing openings 5 on its downward movement and opening the same on its upward movement. Slidably mounted in plunger 6 are, in the present case, two tubes 8-8, the said tubes passing through the head of plunger 6 and communicating with the interior of chamber 3. These tubes are preferably made of the proper size to occupy a space in the can when extended thereinto as shown of substantially the same cubic dimensions as the space between the head of the plunger 6 and the discharge opening 4.

The plunger 6 and tubes 8 are moved in opposite directions by one movement of the hand lever in the following manner.

A hand lever 9 is mounted on a shaft 10 mounted to revolve in suitable bearings 11-12 in the hopper 1 and chamber 3 respectively. On shaft 10 is arranged an arm 13 pivotally connected to a link 14 which is in turn pivotally connected to a lever 15 pivotally mounted on the inner wall of chamber 3 as at 16 and engaging a pin 17 on piston rod 18 through the medium of slot 19. The handle 9 being moved downwardly to a position 9^a indicated in dotted lines, the several parts described assume the positions indicated in dotted lines thereby moving the plunger down to the position 6^a, cutting off the flow of material through openings 5 and closing discharge opening 4.

Mounted on shaft 10 is a second arm 20 pivotally connected to a link 21 which is in turn pivotally connected to a lever 22 pivotally mounted on the inner wall of chamber 3 as at 23 and engaging a pin 24 on bar 25 joining the tubes 8 through the medium of slot 26. When handle 9 is moved into the position 9^a these several parts take the positions indicated in dotted lines thereby withdrawing tubes 8 into chamber 3 as shown.

Since the can to be filled must be raised into a filling position and again lowered

from said position after filling the following mechanism is provided for effecting said movements in proper relation to the movements of the plunger and tubes. An 5 arm 27 is mounted on shaft 10 outside of chamber 3, and a link 28 is pivotally connected thereto as at 29 and to end 30 of a bell-crank 31, the said bell-crank being mounted on a support 32. The other end 33 10 of bell-crank 31 is provided with a slot 34 engaging a pin 35 on a rod 36 movable horizontally in bearings 37. Bearings 37, however, are arranged in different horizontal planes and the intermediate portion of rod 15 36 is provided with a cam slot 38. In cam slot 38 is arranged a pin 39 mounted on a rod 40 movable vertically in bearing 41 and carrying a plate 42 to receive the cans, the said rod 40 being positioned in axial alignment with the chamber 3 and rod 18. When handle 9 is moved to the position 9^a these several parts are actuated to the positions indicated in dotted lines thereby lowering the plate 42 and the filled can thereon, the 20 can of course now being removed and replaced with an empty can.

An upward movement of handle 9 to its original position simultaneously operates the several mechanisms back to the positions 30 shown in solid lines thereby permitting material to flow from the hopper 1 through openings 5 and opening 4 into the can 43, the said can being held tightly against the bottom of hopper 1 during this operation.

35 While the material is permitted to flow freely into the can in the device described, the steam trapped therein readily passes out through tubes 8 into chamber 3 so that no surplus steam remains in the can when 40 sealed. The can filling operation is rendered still more perfect by the simultaneous movements of the plunger 6 and tubes 8 in opposite directions because the space vacated by the tubes 8 is just sufficient to receive 45 the additional material advanced into the can by plunger 6. The steam in chamber 3 is discharged into the atmosphere through discharge pipe 44.

From the foregoing description it may 50 readily be seen that I have provided a machine that is quickly and easily operated, that is positive in operation, clean and sanitary, and economical to manufacture. The form of the cam slot is, of course, such that 55 the raising and lowering of the can will take place in proper relation to the movements of the plunger and tubes.

It is to be understood that while I have 60 herein shown and described one particular embodiment of my invention it is to be considered as illustrative only and in no way to limit the scope of the appended claims.

I claim:

1. A canning machine including a hopper

having a discharge opening formed therein, 65 means for supporting a can in operative relation to said opening, a chamber arranged above said opening and provided with a passage to said hopper, a plunger operatively mounted in said chamber to open and close said passage, an element mounted to reciprocate through said plunger and extend into a can positioned therebelow, and means for operating said plunger and element in opposite directions. 75

2. A canning machine including a hopper having a discharge opening formed therein, means for supporting a can in operative relation to said opening, a chamber arranged above said opening and provided with a 80 passage to said hopper, a plunger operatively mounted in said chamber to open and close said passage and discharge opening, an element mounted to reciprocate through said plunger and extend into a can positioned 85 therebelow, and means for operating said plunger and element in opposite directions.

3. A canning machine including a hopper having a discharge opening formed therein, 90 means for supporting a can in operative relation to said opening, a chamber arranged above said opening and provided with a passage to said hopper, a plunger operatively mounted in said chamber to open and close said passage and discharge opening, 95 an open ended hollow rod mounted to reciprocate through said plunger and extend into a can positioned therebelow, and means for operating said plunger and rod in opposite directions. 100

4. A canning machine including a hopper having a discharge opening formed therein, means for supporting a can in operative relation to said opening, a chamber arranged above said opening and provided with a 105 passage to said hopper, a plunger operatively mounted in said chamber to open and close said passage, an element mounted to reciprocate through said plunger and extend into a can positioned therebelow, and means for 110 operating said plunger and rod in opposite directions, said chamber being provided with discharge to the atmosphere.

5. A canning machine including a hopper having a discharge opening in the bottom 115 thereof, means for supporting a can in operative relation to said opening, a chamber arranged over said opening and communicating therewith and provided with a passage to said hopper at its lower end, a plunger 120 operatively mounted in said chamber to open and close said passage, one or more elements mounted to reciprocate through said plunger and opening and occupying a space below said plunger when extended substantially 125 equal to the displacement effected by said plunger, and means for operating said plunger and element or elements in opposite

directions whereby said element or elements are alternately withdrawn to said opening or extended therethrough.

6. A canning machine including a hopper having a discharge opening in the bottom thereof, means for supporting a can in operative relation to said opening, a chamber arranged over said opening and communicating therewith and provided with a passage 10 to said hopper at its lower end, a plunger operatively mounted in said chamber to open and close said passage, one or more elements mounted to reciprocate through said plunger and opening, a rod attached to said plunger, 15 a shaft revolvably mounted in angular relation to said rod, a pair of arms mounted on said shaft, a link connected to each arm, a lever mounted on the wall of said chamber adjacent to each link and connected thereto, 20 one of said levers being connected to the plunger and the other to said element or elements whereby the rotation of said shaft will actuate said plunger and element or elements a predetermined distance in opposite directions.

7. A canning machine including a hopper having a discharge opening formed therein, means for supporting a can in operative

relation to said opening, a chamber arranged above said opening and provided with a 30 passage to said hopper, a plunger operatively mounted in said chamber to open and close said passage, an element mounted to reciprocate through said plunger and extend into a can positioned therebelow, and means for 35 operating said plunger and can supporting means in one direction and said element in the opposite direction.

8. A canning machine including a hopper having a discharge opening formed therein, 40 means for supporting a can in operative relation to said opening, a chamber arranged above said opening and provided with a passage to said hopper, a plunger operatively mounted in said chamber to open and 45 close said passage, an element mounted to reciprocate through said plunger and extend into a can positioned therebelow, and means for operating said plunger and element in opposite directions and said can 50 supporting means in the same direction as said plunger but in advance of its upward movement and subsequently to its downward movement.

REUBEN R. ERICH.
